UNITED STATES PATENT OFFICE.

GUSTAV A. KRUTTSCHNITT, OF NEWARK, NEW JERSEY.

DESIGN FOR A POCKET-PIECE OR SIMILAR ARTICLE.

SPECIFICATION forming part of Design No. 35,916, dated May 20, 1902.

Application filed January 26, 1902. Serial No. 91,296. Term of patent 7 years.

To all whom it may concern:

Be it known that I, GUSTAV A. KRUTTSCHNITT, a citizen of the United States, residing at Newark, in the county of Essex and State of New Jersey, have invented and produced a new and original Design for Pocket-Pieces or Similar Articles, of which the following is a specification, reference being had to the accompanying drawings, forming part thereof.

Figure 1 is a plan view of the face of a pocket-piece, showing my design. Fig. 2 is a top edge view of Fig. 1.

The leading feature of my design consists of the circular-shaped disk having upon its face the representation of twelve horseshoes arranged circumferentially on same, so as to form its indented surrounding edge, having within them the twelve signs of the Zodiac.

In the drawings, A designates the circular-shaped disk surrounded by the twelve horseshoes B and having further within the horseshoes representations of the twelve signs of the Zodiac, (designated by the reference-letter b' on the drawings.)

What I claim is—

The design for a pocket-piece or similar article substantially as shown and described.

Signed at Newark, in the county of Essex and State of New Jersey, this 23d day of January, 1902.

GUSTAV A. KRUTTSCHNITT.
